UNITED STATES PATENT OFFICE.

WILLIAM JOSEPH STILL, OF LONDON, ENGLAND.

CYLINDER OF INTERNAL-COMBUSTION ENGINES.

1,316,749.

Specification of Letters Patent. Patented Sept. 23, 1919.

Application filed May 19, 1919. Serial No. 298,205.

To all whom it may concern:

Be it known that I, WILLIAM JOSEPH STILL, of 7 Princes street, London, S. W. 1., England, engineer, have invented certain new and useful Improvements in and Connected with the Cylinders of Internal-Combustion Engines, of which the following is a specification.

This invention relates to improvements in and connected with the cylinders of internal combustion engines, and has particular reference to cylinders of large diameter where the combustion pressures are taken by a thin cylinder or liner supported externally by a pressure resisting sleeve in accordance with the principle set out in the specification of my prior British Letters Patent No. 1750 of 1912. In this prior case the pressure resisting sleeve also forms the outer jacket or mantle of the cylinder, the cooling medium circulating through the ribs on the thin cylinder or liner between the liner and the sleeve. Such an arrangement has proved satisfactory in engines having cylinders of comparatively small size, but where larger cylinders are concerned it becomes more difficult to support the thin cylinders or liners without the possibility of distortion due to movement of the material of which the pressure resisting sleeve is composed. This is due to the sleeve being a casting—usually of steel—of irregular shape and even when annealed not of sufficiently homogeneous material. The consequence is that such structures tend to change in shape in time, and large and relatively thin cylinders or liners cannot resist these distorting influences, although, as aforesaid, the smaller and relatively thicker ones do. It therefore becomes important that for large cylinders the pressure resisting sleeves be of regular shape and of homogeneous material. It is also important in these large cylinders that the cylinder or liner and the pressure resisting sleeve should approximate in temperature as closely as possible, and the primary object of my invention is to provide a cylinder construction in which these desiderata are attained, and the primary feature of the invention consists in forming the pressure resisting sleeve in the form of a hoop and locating it within the jacket and consequently immersed in the jacket water or other cooling medium instead of using it as the jacket or mantle. By reason of this the hoop forming the pressure resisting

sleeve can be a forging of regular shape of mild steel or wrought iron since it is no longer necessary to form upon it the bosses for the water inlet and outlet passages nor those necessary for effecting attachment to the engine crank case.

In the accompanying drawings I have illustrated my invention, Figure 1 being a sectional view illustrating a cylinder constructed in accordance with my invention.

Fig. 2 is a sectional plan view thereof, the left-hand half of the figure being a section on the line 2—2 and the right-hand half a section on the line 2^a—2^a.

Fig. 3 is a view similar to Fig. 1 of a modified construction.

Fig. 4 is a sectional view thereof, the left-hand half of the section being on the line 4—4 with the pressure resisting sleeve or hoop removed and the right-hand half being a section on the line 4^a—4^a, the sectioning of the pressure resisting sleeve or hoop being omitted for the sake of clearness.

Fig. 5 is a sectional view indicating a further possible modification of the arrangement shown in Fig. 3, and Fig. 6 is a view illustrating a modified construction of the exhaustion port entablature of the liner.

Referring to these drawings and particularly to Fig. 1 the numeral 1 designates the thin cylinder or liner which is cast with ribs 2, and 3 designates a wrought iron or mild steel hoop which constitutes a pressure resisting sleeve which is forced over the ribs 2, and in this example has a conical deflecting plate 4 attached to it at the top. The outer jacket or mantle 5 of the cylinder surrounds the whole and is bolted to the adjoining cylinder member, a joint 7 being formed between the thin cylinder or liner 1 and the jacket or mantle 5. It will be seen that the hoop or pressure resisting sleeve 3 is of regular form and is completely immersed in the jacket water and must approximate in temperature to the temperature of the jacket water. The importance of this is that the temperature difference between the thin cylinder or liner 1 and the hoop 3 which constitutes the pressure resisting sleeve is much less than would be the case if the outer jacket itself constituted the pressure resisting sleeve as in the prior case above alluded to. It may be mentioned that it has been found by trial that the temperature of the outer jacket or mantle falls considerably below the average temperature of the cool-

ing medium within it and temperature differences amounting to over 100° F. between the thin cylinder or liner and the jacket or mantle have been recorded.

- 5 Such differences are detrimental where the two are united together to resist stresses and by locating the pressure resisting hoop completely immersed within the jacket water as before described combined with the elimination of all radiation losses from it will be found very advantageous particularly where large structures are concerned. Moreover the hoop 3 forms a dividing wall between the hotter water mixed with steam bubbles 10 ascending between it and the ribs 2 and the cooling water located between it and the outer jacket or mantle 5. This promotes a rapid circulation of the water within the jacket in the direction indicated by the arrows in Fig. 1, the hotter and lighter water column flowing rapidly up between the ribs 2 giving up its steam at some point above the deflecting cone 4 and passing down outside the hoop 3.
- 15 20 25 Such an arrangement causes a very rapid circulation of the water, the liner velocity of the flow over the heating surfaces of the thin cylinder or, liner far exceeding what can be provided for by circulation through an entire system of jackets and connecting pipes to and from a boiler or radiator even with the assistance of a forced circulation system of any reasonable size. This high rate of flow tends further to reduce the temperature difference between the hoop 3 and the thin cylinder or liner 1 and between the liner and the circulating water, and this permits of the maintenance of higher mean pressure within the cylinder than could otherwise be safely employed. The rapidity of circulation also tends to discourage the deposition of scale or other matters on the liner surfaces. In very large engines the cross section of the ribs 2 on the thin cylinder or liner 1 may be increased at the outside 30 35 40 45 50 55 as at 7 in Fig. 4. This could not be done if the temperature difference between the inner surface of the liner and its outer edge where it engages the hoop 3, was great because the liner face would be crushed by its inability to expand in accordance with its rise in temperature, thus the foregoing construction permits the cross section of outer edges of the ribs 2 to be enlarged to any required extent to provide adequate support for the longitudinal stresses.

In Fig. 3 the hoop 3 is shown with an extension 3_a which supports the extended form of the combustion chamber of the cylinder, but it will be noticed that it still retains its characteristic of being of regular form capable of being forged from wrought iron or mild steel.

In the form here shown the hoop 3 supports the radial stresses and the longitudi-

nal stresses are also supported by means of the T headed bolts 8, the heads 8_a of which engage in slots 9 formed by cutting an annular groove in the ribs. These T headed bolts 8 are inserted in position with their heads 8_a in the slots 9 before the hoop is pressed into place over the ribs 2. These bolts 8 when locked home by the nuts 10 extend the support given by the ribs 2 to the control end of the combustion chamber 75 and enable the extension 3_a to resist both radial and longitudinal stresses. If desirable further support for the longitudinal reactions may be provided for by means of through bolts 10_a connected to the hoop 3 as 80 indicated in Fig. 3, these bolts being immersed in the cooling water of the jacket.

Fig. 5 shows how it is possible to fit additional hoops 3_b around the extension of the combustion chamber to resist radial bursting 85 stresses.

The foregoing construction enables an increased combustion pressure to be safely maintained in the combustion end of the cylinder.

What I claim and desire to secure by Letters Patent is:—

1. An internal combustion engine cylinder comprising a thin cylinder or liner having longitudinal ribs on its outer side, a pressure 95 resisting sleeve embracing the ribs and spaced by the ribs from the liner and serving to withstand the pressure imparted to the sleeve through the ribs, and an outer jacket inclosing the liner and sleeve and 100 spaced from the latter, so that the sleeve is immersed and its inner and outer surfaces are in contact with the cooling fluid in the jacket and temperature difference between the sleeve and the liner is minimized. 105

2. An internal combustion engine cylinder comprising a thin cylinder or liner having longitudinal ribs on its outer side, a plurality of pressure resisting sleeves embracing the ribs and spaced by the ribs from the liner and serving to withstand the pressure imparted to the sleeves through the ribs, and an outer jacket inclosing the liner and sleeves and spaced from the latter so that the sleeves are immersed and their inner and outer surfaces are in contact with the cooling fluid in the jacket and temperature difference between the sleeves and the liner is minimized. 110 115

3. In an internal combustion engine having its cylinder formed according to claim 1, the provision of T-headed bolts whose heads engage in slots in the ribs of the thin cylinder and are secured by nuts to the pressure resisting sleeve whereby said sleeve is capable of resisting longitudinal strains. 120

4. An internal combustion engine as set forth in claim 1 wherein longitudinal strains are resisted by through bolts located in the cooling jacket.

5. An internal combustion engine cylinder 130

- comprising a thin cylinder or liner having longitudinal ribs on its outer side, a pressure resisting sleeve embracing the ribs and spaced by the ribs from the liner, said sleeve being a forged hoop of regular form and serving to withstand the pressures imparted to the sleeve through the ribs, and an outer jacket inclosing the liner and sleeve and spaced from the latter so that the sleeve is immersed and its inner and outer surfaces are in contact with the cooling fluid in the jacket and temperature difference between the sleeve and the liner is minimized.
6. An internal combustion engine cylinder as set forth in claim 1 having a conical deflector attached to it at one end. 15
7. An internal combustion engine cylinder as set forth in claim 1 wherein the pressure resisting hoop is formed with an integral extension which serves both as a deflector 20 and as a means of resisting both radial and longitudinal stresses imparted to it by the thin cylinder or liner.

In witness whereof I affix my signature.

WILLIAM JOSEPH STILL.
